STOVEPIPE CASING

Application filed October 22, 1924. Serial No. 745,117.

This invention relates to the oil well industry, and it relates particularly to stovepipe casing utilized therein.

As an oil well is drilled, a well casing is advanced into the hole for reinforcing the wall against cave-ins, excluding ground water and for other purposes. Two types of casing may be used for this purpose, screw casing and stovepipe casing. Screw casing is made up from sheet wrought iron which is rolled into circular form and welded. Each end of the casing is provided with screw threads which are arranged to be screwed into couplings or other members for securing them together. Stovepipe casing of the present type comprises inner and outer layers of comparatively soft sheet metal which are rolled into circular form and secured together either by riveting, by welding or by rolling inter-engaging corrugations in the two layers after they are placed together. In other words, it is general practice to form stovepipe casing by staggering the sections relative to each other so that the abutting ends of the sections of the inner member are offset relatively to the abutting ends of the outer member, these two members being secured together in any of the above mentioned manners in order to form the stovepipe casing in a continuous piece.

One of the great disadvantages found in using either screw casing or the present stovepipe casing is that neither of these casings will withstand substantially any frictional wear. This is due to the fact that they are both made of a comparatively soft material. The stovepipe casing must be made of a comparatively soft material because of the necessity of securing the inner and outer layers together, and this securing necessitates the punching, welding, riveting or forming of corrugations in both of the layers of this type of stovepipe casing. When drilling in hard strata such as rock, the drill progresses very slowly. If the hole is out of alignment or the drill pipe is bowed, tool joints of the string of drill pipe will engage with the well casing at various points. This produces a considerable wear at one place and both screw casing and the present stovepipe casing wear

through very readily, owing to the softness of the material which the manufacturers are compelled to use as is previously explained. The wearing through of the casing causes the string of well casing to separate which is obviously detrimental. In the present stovepipe casing it is found that the casing will separate even when only the inner layer thereof is worn through. This is due to the fact that the forming of the stovepipe in a continuous length depends upon the cooperation between the inner and outer layers thereof. When the inner layer is worn through, it fails to perform its function and the casing will separate or cause leakage.

It is an object of this invention to provide a stovepipe casing which will possess a tensile strength equivalent to that of any of the present casings, but in addition to which will possess frictional resisting qualities which enormously exceed that of any of the present type of casings whether it be screw casing or stovepipe casing. I am able to accomplish this due to the novel construction of my invention. The stovepipe casing of my invention consists of inner and outer layers of material. The outer layer of the casing is formed of soft steel or a fairly ductile material which is of such a character that it may be readily formed in such a manner as to provide joints therein necessary for securing portions thereof together to form a continuous member. The outside layer is solely for the purpose of providing the tensile strength necessary for the casing. The inner layer of my stovepipe casing comprises a tubular shaped member which is placed inside the outer layer and which has absolutely no joints of any character, and which is in no way attached to the outer layer. Owing to this, it is possible for me to make the inside layer of my casing of a material which is of an extremely hard character. In practice the material from which I form the inner member is of a hardness which is substantially 200 per cent greater than that used in any other casing of which I have knowledge. The outer member of my invention is arranged to take all of the tensile strains which may be placed on a casing, and the

inner member is arranged to receive all of the friction which may be placed on a casing. It is not probable that the inner layer will be worn through due to friction because of its great hardness and great resistance to frictional wear. If, however, this inner member should be worn through, the casing will not separate because of the fact that the inner layer in no way cooperates with the outer layer to provide the casing in continuous form.

It is another object of the invention to provide a joint for a casing of this character which will not leak.

It is also an object of the invention to provide a stovepipe casing which will have great radial strength. I accomplish this object by providing the outer layer in very short lengths which are joined together by fluid-tight joints of my invention. These joints being of such a character as to provide great radial strength are situated fairly close together and therefore provide a stovepipe casing having a great radial strength.

It is another object of the invention to provide a stovepipe casing of this character which is easy to install, economical to provide and superior to other stovepipe casings in the above mentioned respect.

Other objects and the especial advantages of this invention will be made evident hereinafter.

Referring to the drawings which are for illustrative purposes only,

Fig. 1 is a vertical sectional view through a stovepipe casing presenting the features of my invention.

Fig. 2 is a view showing the joint structure provided by my invention, this view showing the members in position ready to be secured together.

Fig. 3 is a section of the joint shown in Fig. 2, but being shown secured together.

Fig. 4 is a horizontal section taken as indicated by the line 4—4 of Fig. 3.

With reference to the drawings, I provide an outer tubular member 11 which is made up of sections 12, these sections 12 being made from sheet metal possessing sufficient ductility to permit forming of joints for securing these sections together. I provide a joint for securing sections 12 together, as shown clearly in Figs. 2, 3 and 4. With particular reference to Fig. 2, the lower end of each of the sections 12 is provided with an annular external lip 14 which is provided by bending the end of the section back on itself, as clearly shown in Fig. 3. On the upper end of each

of the sections 12 I provide a bell portion 15, the end of which is provided with an internal retaining lip 16. The internal diameter of the bell portion 15 is of such size as to be of the same diameter as the external face of the lip 14 on the lower end of each member 12.

The bell portion 15 is provided with an open

seam 18, as shown in Fig. 2 to permit the insertion of the lip 14 on the lower end of each member 12, as will be described later. Placed adjacent to the upper face 20 of the lip 14 is a packing member 21, this packing member 21 being of an external diameter which is slightly larger than the external diameter of the lip 14, as clearly shown in Fig. 2.

In securing the lower and upper ends of the adjacent outer tubular sections 12, the sections are first disposed as shown in Fig. 2. The bell portion 15 is then expanded as indicated by the dotted lines 23 of this figure in any suitable manner, such as by driving a wedge into the open seam 18. It will be seen that this expanding is necessary to permit the passing of the lip 14 into the interior of the bell portion 15 past the internal retaining lip 16 thereof. After the lip 14 has been inserted, as shown in Fig. 3, the bell portion 15 may be allowed to return to its normal position. A suitable clamp, not shown, may then be utilized for contracting the bell portion 15 around the lower end of the upper section 12 and the open seam 18 thereof welded, as indicated at 25 in Fig. 4. Owing to the fact that the external diameter of the packing 21 is slightly larger than the external diameter 14 of the upper member, the packing member will be compressed when the bell portion 15 is constricted therearound, and provides a fluidtight seal between the sections.

The inner tubular member 30 is comprised of sections 31, these sections being made up of lengths of very hard sheet steel rolled into tubular form. These lengths may be welded together as indicated at 32 to form the sections 31.

As shown in Fig. 1, a section 31 of the inner tubular member 30 is inserted into the lower section 33 of the outer tubular member as shown at 34. An outer tubular member 35 is then telescoped over the upper end of the section 31 and a joint between the sections 33 and 35 is made, as previously described. Another inner tubular section 37 is then installed, this section 37 telescoping inside the outer section 35, the upper end thereof projecting a short distance above the upper end of the section 35, the lower end thereof abutting with the upper end of the section 31 as indicated at 38. After this, another outer tubular section 39 is joined with the section 35, after which another inner tubular section 115 may be installed. It will be seen that this procedure may be continuously carried out as the stovepipe casing is assembled.

It is not absolutely essential that the short lengths of the inner member be welded together to form the sections 31. In some cases I have merely abutted the ends of these lengths together inside the outer member and have then galvanized the assembly.

In practice, the outer sections 11 and 12 are

of a length of about five feet. This means that there is a joint every five feet in the casing. The joint is of such a character, as is obvious from the drawings, that it will be much stronger than the tensile strength of a single layer. At the joint the layers are bent in such a manner as to be doubled and should, therefore, provide a strength which should approach nearly twice that of a single thickness of material. By placing these joints very close together, I am able to provide a casing which has very high radial resisting strength. Sections such as 11 and 12 are assembled together in lengths of 25 to 30 feet at the shop. When the casing is installed in a well, these lengths are in turn secured together by similar joints. This practice eliminates considerable work at the well and increases the economy of the casing and convenience for the installation thereof.

From the foregoing description, it will be seen that a stovepipe casing of this character is very economical to provide and may be very readily installed, owing to the fact that the cost of material and the cost of making is comparatively small, and that the joints of the outer tubular member 11 may be very easily and quickly made. The joints provided in the outer tubular member are absolutely impervious to fluid providing a reliable and permanent seal between the sections 12. My casing has high radial compressive resistance as well as considerable axial strength. The outer member being made of a ductile material permits the forming of the joints and the providing of the outer tubular member in continuous form so as to provide the necessary tensile strength for the casing. The inner member is made of hard steel plates, this being permitted due to the unique construction previously explained, these steel plates being of a hardness which exceeds that of any material used at the present time in casings.

From the foregoing description, it will be seen that my invention is based almost entirely upon the use of an outer member which supplies tensile strength, and an inner member which supplies high frictional resisting qualities, these members being very independent of each other as a matter of function. The outside layer or member provided by my invention provides a continuous member which is equivalent to the other casings, screw type or stovepipe, as regarding tensile strength. By the utilization of the inner member which may be considered as a liner for the outer member, the casing provided by my invention is possessed of frictional resisting qualities which very greatly exceeds that of any casing known in this art. For this reason I consider stovepipe casing of my invention greatly superior to any other casing on the market at the present time.

I claim as my invention:

1. A joint for stovepipe casing comprising: a first member having its end portion bent back along and in close contact with the outer surface of its body portion to form an annular exterior lip; a second member having a belled portion formed at the end thereof into which said end of said first member extends, and having its end portion bent back along and in close contact with the inner surface of its body portion to form an internal retaining lip; and a packing member disposed between the adjacent faces of said annular lip of said first member and said retaining lip of said second member.

2. A stovepipe casing coupling comprising: two casing sections, an end of one extending within an end of the other to provide an annular inter-tubular space; annular elements disposed in said space, one of said elements being provided upon each of said sections, said elements being axially opposed to each other to prevent the parting of said coupling; and a tubular lining disposed tightly within said sections and supporting the end of said inner casing section of said coupling against a tendency of said end to collapse inwardly.

3. A stovepipe casing coupling comprising: two casing sections an end of one extending within an end of the other to provide an annular inter-tubular space; annular elements disposed in said space, one of said elements being provided upon each of said sections, said elements being axially opposed to each other to prevent the parting of said coupling; a tubular lining disposed tightly within said sections and supporting the end of said inner casing section of said coupling against a tendency of said end to collapse inwardly; and an annular packing member disposed in said inter-tubular space between said annular elements.

4. A joint for stovepipe casing comprising: a first member having its end portion bent back along and in close contact with the outer surface of its body portion to form an annular exterior lip; and a second member having a belled portion formed at the end thereof and into which said end of said first member extends, and having its end portion bent back along and in close contact with the inner surface of its body portion to form an internal retaining lip.

5. A stovepipe casing coupling adapted to withstand abnormal tension stresses, and comprising: two casing sections, an end of one extending inside an end of the other to provide an annular inter-tubular space; opposing elements disposed in said space and supported against crushing by the portions of said sections which bound said space, one of said elements being secured to each of said sections so as to lock said sections against axial separation and means disposed within

the end of said inside casing section to prevent the collapsing of said end.

6. A joint for stovepipe casing comprising: a primary tubular member; a locking element outwardly and reversely bent from an end thereof; a secondary tubular member having a belled portion formed at an end thereof; a locking element inwardly and reversely bent from said end of said secondary member, said end of said primary member being disposed in said belled portion so that said locking elements inter-lock and a tubular insert snugly fitting within said primary and secondary members and resisting a tendency of said primary member to collapse inwardly.

7. A method of joining two sections in the formation of stovepipe casing, said method comprising: forming an outwardly extending rigid locking element on an end of a primary section; forming an end of a secondary section so that it is belled and split; forming an inwardly extending rigid locking element upon said end of said secondary section so that this will pass over said outwardly extending locking element; projecting said end of said primary section into said belled and split end of said secondary section; contracting said secondary section end upon said primary section end; and welding opposite edges of said secondary section split to retain said sections locked together by opposition of said locking elements.

8. A method of joining two sections in the formation of stovepipe casing, said method comprising: forming an outwardly extending rigid locking element on an end of a primary section; forming an end of a secondary section so that it is belled and split; forming an inwardly extending rigid locking element upon said end of said secondary section so that this will pass over said outwardly extending locking element; projecting said end of said primary section into said belled and split end of said secondary section; contracting said secondary section end upon said primary section end; and joining opposite edges of said secondary section split to retain said sections locked together by opposition of said locking elements.

9. A method of joining two sections of tubing of substantially equal and uniform diameter which consists in forming an outwardly extending rigid flange upon a male end of one of said sections by outward and reverse bending of the metal thereof, forming an inwardly extending rigid flange upon a female end of the other section by an inward and reverse bending of the metal thereof, expanding the metal of said female end into a split bell so that said male flange may be received therein past said female flange, contracting said bell about said male end so that said male flange and said female flange

interlock, and securing the split edges of said bell together.

In testimony whereof, I have hereunto set my hand at Los Angeles, California, this 16th day of October, 1924.
